UNITED STATES PATENT OFFICE.

JOHN A. EVARTS, OF WEST MERIDEN, CONNECTICUT, ASSIGNOR TO THE
BRADLEY & HUBBARD MANUFACTURING COMPANY, OF SAME PLACE.

SHADE-HOLDER.

SPECIFICATION forming part of Letters Patent No. 224,411, dated February 10, 1880.

Application filed July 19, 1879.

To all whom it may concern:

Be it known that I, JOHN A. EVARTS, of West Meriden, in the county of New Haven and State of Connecticut, have invented a new 5 Improvement in Extension-Lamp Fixtures; and I do hereby declare the following, when taken in connection with the accompanying drawings and the letters of reference marked thereon, to be a full, clear, and exact description of the same, and which said drawings constitute part of this specification, and represent, in—

Figure 1, a side view, partly in section; Fig. 2, a vertical section of the upper part; 15 Fig. 3, a section at the shade-ring; Fig. 4, a view of the shade and ring, looking up.

This invention relates to an improvement in that class of fixtures used for suspending lamps from the ceiling, and which may be 20 raised or lowered at pleasure.

In this and similar classes of fixtures the shade-ring has been made to extend down around the outside of the neck of the shade, then screws inserted radially and so as to engage in the groove of the neck of the shade. 25 This construction necessitates a large or apparently heavy ring, and the screws are exposed to view.

The object of this invention is to avoid these 30 unsightly parts of the fixture; and it consists in the construction hereinafter described, and more particularly recited in the claim.

A represents the lamp or lamp-holder, from 35 which rods B B extend upward and are united to a single central rod, c. This rod c is arranged to slide freely up and down in a stationary tube, D, the said tube being suspended from the ceiling in the usual manner for hanging or securing such fixtures. At the top of 40 the tube D are two (more or less) pulleys, E, and around the tube D is the weight F; or it may be otherwise arranged.

Chains a or other suitable devices are attached by one end to the upper end of the central rod, c, and run over the pulleys E outward 45

and downward, the other end being attached to the counterbalancing-weight F; hence, when the lamp is pulled down, the chains run down inside the tube D with the rod c, thus leaving only the single run of the chain exposed. This construction also gives a greater strength and firmness to the fixture than when the chains extend directly to the shade-ring. 50

H is the shade-ring. In this case it is made fast to the rods B, and need be but a simple flat ring a little larger in external diameter than the neck of the shade. Vertically through this ring several screws, d, are arranged so that their heads will extend outward beyond the interior of the opening in the neck of the shade, and so that when the shade is set upon the ring, as seen in Fig. 3, the heads of the screws d may be turned to bear upon the inner surface of the shade and secure it to the ring, as in Figs. 3 and 4. By this construction the 65 usual clumsy ring and outside screws are avoided and a most secure engagement of shade and ring insured.

Two hook-shaped lugs may be formed upon or attached to the ring in place of two screws 70 as supports. In that case a single screw will be sufficient. This part of the invention is applicable to holding shades other than for extension-fixtures.

I do not wish to be understood as broadly 75 claiming supporting a lamp-shade from the inside, as such I am aware is not new.

I claim—

The herein-described shade-support, consisting of the ring to rest upon the top of the 80 shade, combined with supports extending down within and beneath the neck, one of which supports is a screw arranged so that its head will bear upward upon the inside of the neck of the shade, all substantially as described. 85

JOHN A. EVARTS.
